UNITED STATES PATENT OFFICE.

ALLEN BRADFORD, OF PORTLAND, OREGON.

AIRSHIP.

Application filed January 25, 1928. Serial No. 83,759.

My invention consists of improvements in air ships which dispenses with numerous circular frames and other connecting frame work, and substitutes frames occupying less than one half their space occupied in the ships previously designed and built, and so connected with a longitudinal truss extending the entire length of the ship, an upright stem at the bow, and a similar upright stern post, to form a frame entirely in the lower part of the ship. And one or more large long cylinder reservoirs, each divided longitudinally by a gas tight flexible diaphragm throughout its length, and thus adapted to store gas temporarily, or hold compressed air for ballast, as may be required, and firmly attached to said frame, a long car, the whole length of the ship and over said reservoir cylinders a light-weight strong floor which forms the bottom of the gas-holder, and strengthens the ship against lateral strains. This gas holder takes the place of the numerous gas bags usually employed. The upper part of the gas holder is collapsible, formed of strong gas tight fabric, reinforced by cementing on a narrow strip of same fabric, to form a double thick border around the edge of said fabric for increased strength where it is bolted to the horizontal frames which connects the upper ends of the frames (24). There are a few circular frames and connecting ribs necessary to shape the bow and the stern of the ship.

In the drawings, Fig. 1 is a longitudinal vertical section showing the truss which stiffens the ship vertically, and the bow and stern frame work which shapes the ends of the ship. Fig. 2 is a plan view below the line 17^a. Fig. 3 is a plan view below the line 111—111 in Fig. 4. Fig. 4 is a transverse vertical section of the keel parts or main frame of the ship. Fig. 5 is an enlarged view of the junction segment frames with the longitudinal part 17^a. Fig. 6 is an enlarged section of one of the reservoir cylinders. Fig. 7 is a detail of the posts which support the upper part of the reservoir cylinders and semi-circular ribs which support the thin sheet metal of the upper half of the cylinder when the air pressure within is not sufficient to keep it from collapsing.

(2—3—4—5—6) Fig. 1 are circular frames at the bow, similar frames are shown at the stern. (7—8—9—10) are longitudinal ribs at the bow. There are similar ribs at the stern. (11) is the stem post very strongly secured to the longitudinal truss, which consists of the bottom girder (12) the upright struts or posts (13) the tension rods, (14) and the top girder immediately under the floor (15). This floor is constructed with joists running cross-wise of the ship and firmly secured to the frames (24) at each side of the ship, and boards lengthwise, making a light-weight floor, offering great resistance to lateral strains. This floor covered with gas tight fabric which extends up inside the frames (24) to join with (17^a) Fig. 4 forms the bottom of the gas-holder.

(11) braced by (30) and other ribs forms a stem post of sufficient strength to draw the inflated gas holder against the frictional resistance of the atmosphere when traveling, by means of numerous straps fastened to the fabric, and at the other end with a hole to engage with button-like knobs (41) on the largest circular frame (6). The inflated gas-holder is fastened to the rear frames in like manner.

(20) is the floor of the car. It is secured to the lower chord (12) of the truss. This truss is indicated by broken lines in Fig. 3 making an open work partition lengthwise of the car. This truss occupies the full height of the car connecting with the floor (15).

The gas holder shown inflated in Fig. 1 made of strong flexible gas-tight fabric (19), is strongly secured to the rib (17^a), Fig. 5 where it connects gas tight with the gas tight covering of the floor (15), and when deflated collapses onto said floor. This gas holder takes the place of numerous gas bags as air ships are usually constructed.

This gas holder may be inflated with air of sufficient pressure from any suitable source to sustain the fabric, to test for leakages and kept inflated Fig. 4 while workmen enter through the airlock (42) Figs. 1 and 2, erect scaffolding and varnish the inside of the fabric with rubber or other varnish and line the inside surface with gold-beater skins, bringing scaffold materials through the airlock which has a door high enough to admit lumber of considerable length, this airlock having an air-tight, gas-tight trap door in the

floor (15). When the varnish is dry and materials of scaffold removed, the fabric may be allowed to collapse onto floor (15) excluding all air. It is then ready to inflate with 60 gas. A sufficient number of relief valves may be fixed between the upper ends of the frames (24) arranged to open automatically whenever the internal pressure become unsafe.

10 Another way to reduce pressure, without losing gas, is provided by the gas pump (28) Fig. 4 and suction pipe (33) by means of which gas may be pumped from the gas holder and stored above the diaphragm in cylinders (22-22). (16) is a floor over the car, which also stiffens the car against lateral strains, and with floor (39) Fig. 4 affords storage room.

15 The circular T shaped uprights (45) secure the car to the frame before described. All of the lower part of the ship below (17) bow and stern frame work to be covered on the outside with thin sheet metal to present a smooth surface to the atmosphere.

20 The reservoir cylinders (22-22) before mentioned are made principally of thin sheet duralumin strengthened with ribs (23) to prevent collapse when the internal pressure is too weak to sustain the weight of the upper part but the duralumin must be strong enough to prevent bursting by internal pressure. The diaphragms (34) are of the right width to form a close fitting lining for the lower half of the cylinder when filled with gas, or

25 to be a similar lining for the upper half when the cylinders are filled with air. These air-gas-tight partitions do not require great strength as the pressure is always equal on each side. (31) is one of the air inlet

30 pipes and (32) is one of the gas inlets. (43) seen in dotted lines behind one of the wood segment supports, in Fig. 6 is one of the self-closing ballast discharge pipes, each having a cord or wire connection to a handle

35 convenient for the engineer. The valve (40) near the top of pipe (32) Fig. 4 is only opened when it is required to allow some gas to pass from the reservoir cylinders to the gas holder. The air pump or

40 compressor (29) Fig. 4 compresses air in the reservoir cylinders below the diaphragms. If there be gas in the cylinders above the diaphragms it is reduced in volume. The gasoline motors (27) are geared to the shafts (25) which are supported on brackets secured to the car and to the seg-

45 ment frames (24) as seen in Figs. 4 and 3 and in dotted lines in Fig. 1. Propellers 26 are fixed on the shafts 25 and rotated therewith.

50 The pipe (32) has a mercury gauge 36 connected to indicate the pressure of air in the cylinders, and the pipe (33) has a mercury gauge 35 to indicate the pressure in the gas holder.

55 It is, of course, understood that in a plant equipped to build airships there is likely to be a compressed air system of large capacity which will be used to inflate the holder 19 for varnishing and testing although obviously a smaller pump may be used if such a large capacity plant is not available.

60 Having described my invention what I wish to secure by Letters Patent is:

1. In an air ship of the buoyant type, one 75 or more long cylinders of light weight construction, made in two halves, upper and lower, bolted together with the edges of a flexible diaphragm or partition of sufficient width to fit against either half cylinder.

2. In an air ship of the buoyant type, the combination of the segment frames (24) with the floor (15) having joists crosswise of the ship secured at both ends to the frames (24) and covered with a light weight, strong floor (15), and the longitudinal truss and stem and stern posts, and rigidly attached long car, making a rigid frame for the ship.

3. An airship comprising a longitudinal truss, end frames connected to the ends of the truss and offset upwardly therefrom, side frames connected to the truss and curving upwardly and outwardly from the truss, a floor connected to the truss and to the curved side frames below the upper edges of the side frames, a gas-tight covering for the floor and side frames, and a flexible gas holder connected to the upper edges of the side frames and co-acting therewith to define a gas space, the forward and rearward ends of the flexible gas holder being engaged by the end frames.

4. An airship comprising a longitudinal truss, side frames curving outwardly and upwardly from the truss, a floor connected to the truss and also connected to the side frames below their upper ends, a gas-tight covering for the floor and the side frames, and a collapsible gas holder connected to the upper ends of the side frames and co-acting therewith to define a gas space.

ALLEN BRADFORD.
